(57) **ABSTRACT**

A new and distinct rose plant having a strong fragrance and bright pink colored flowers with numerous petals.

4 Drawing Sheets

1

Botanical classification: *Rosa L.*

Varietal denomination: 'RNF Pink 03WL'.

BACKGROUND OF THE INVENTION

The present invention comprises a new and distinct cultivar of rose plant known by the varietal name 'RNF Pink 03WL'. The new variety was discovered in April of 2010 in Gifu, Japan. The new variety is the result of a planned breeding program between an unnamed and unpatented *Rosa L.* variety (female parent) from the breeder's own collection and an unnamed and unpatented *Rosa rugosa* variety (male parent) from the breeder's own collection. 'RNF Pink 03WL' has a different flower color than its female parent. Additionally, 'RNF Pink 03WL' exhibits a fragrance like its male parent, but differs from its male parent in its actual fragrance. When 'RNF Pink 03WL' is compared to *Rosa L.* 'Ever172' (currently unpatented in the U.S., Japanese Patent No. 20890), the varieties are similar in flower color, not having eyes on their flowers, and in that they exhibit double flowers. However, when compared to 'Ever172', 'RNF Pink 03WL' has a larger flower size, different number of petals, and exhibits a fragrance. When generally compared to other rose varieties known to the breeder, the new variety differs in its strong fragrance, its type of fragrance, and in flower color. 'RNF Pink 03WL' has been trial and field tested and has been found to retain its distinctive characteristics and remain true to type through successive propagations.

DESCRIPTION OF THE DRAWINGS

The accompanying photographic drawings taken from 3-4 years of age illustrate the new variety, with the color being as nearly true as is possible with color illustrations of this type:

FIG. 1 shows a close-up view of a flower of the new variety;

FIG. 2 shows a view of an entire plant of the new variety;

2

FIG. 3 shows a view of multiple plants of the new variety; and

FIG. 4 shows the leaves of the new variety.

5 DESCRIPTION OF THE PLANT

The following detailed description sets forth the characteristics of the new cultivar. The data which defines these characteristics were collected by asexual reproductions first performed via stem cuttings in May of 2011 carried out in Gifu, Japan. Plants of the new variety were grown in a greenhouse under natural light in 15 cm pots with peat moss substrate and with the assistance of heaters in the winter. The color readings and measurements were taken indoors in a greenhouse under natural light on one year old plants grown in containers. Color references are primarily to The 2015 R.H.S. Colour Chart of The Royal Horticultural Society of London, Sixth Edition.

20 PLANT

Time to initiate roots: About 21-28 days at approximately 25° C.

25 Time to develop roots: About 30-45 days at approximately 25° C.

Time to produce a finished flowering plant from a rooted cutting: About 5 months/20-22 weeks in a 15 cm container.

30 Rooting habit: Having a main root with lateral roots emerging therefrom.

Growth habit: Upright.

Distance from media surface to top of foliage: 30-35 cm at the end of production.

35 Distance from media surface to top of flowers: 35-40 cm.

Plant diameter: Around 25 cm.

Vigor: Average.

Strength (need for artificial support): No artificial support needed.

40 Branching characteristics: Branching from bottom or lower level

Stem color:		5	<i>Shape</i> .—Rounded with a wavy habit. <i>Length</i> .—4-5 cm. <i>Width</i> .—5-6 cm. <i>Apex shape</i> .—Round with a wide lip. <i>Base shape</i> .—Round and narrow. <i>Margin</i> .—Entire. <i>Number per flower</i> .—70. <i>Texture</i> .—Soft. <i>Reflex characteristics</i> .—None. <i>Presence of basal petal spots</i> .—None. <i>Petaloid description</i> .—Lightly fringed with semi-double flowering.
<i>Immature</i> .—N57A.			
<i>Mature</i> .—132D.			
Surface texture:			
<i>Young wood</i> .—Rough, with small thorns present.	10		
<i>Older wood</i> .—Smooth and glossy.			
Average stem diameter: From 7 mm to 1 cm.			
Internode length: Approximately 4 to 5 cm.			
Number of internodes: 6 to 7.			
Thorns:			
<i>Average number</i> .—Main branches: 50 per plant. Stems: 10 per stem.			
<i>Length</i> .—7 mm to 1 cm.			
<i>Width</i> .—Around 5 mm.			
<i>Color</i> .—Ivory/beige (8D).	15		
<i>Shape</i> .—Aristate.			
Foliage:			
<i>Arrangement</i> .—Alternate.			
<i>Average number of leaves per lateral branch</i> .—7.			
<i>Average number of leaflets per leaf</i> .—7.	20		
<i>Overall size of leaf</i> .—Length: 10 cm. Width: 5 cm.			
<i>Leaflet</i> .—Shape of leaf (generally): Ovate. Shape of apex: Acute. Shape of base: Obtuse. Length range: 5-7 cm. Width range: 3-5 cm. Texture: Moist and wet, with weak glossiness on the upper surface. Margin type: Serrate. Color: Young leaves: Upper surface: 141C, with a 64A edge. Lower surface: 145B, with a 64A edge. Mature leaves: Upper surface: 125A. Lower surface: 130B. Veins: Venation type: Pinnate. Color: 138D.			
<i>Petiole</i> .—Length: 2-3 mm. Diameter: 1-2 mm. Color: 139D. Texture: Rough.			
<i>Stipule</i> .—None present.			
INFLORESCENCE			
Buds:			
<i>Number of buds per plant</i> .—10.			
<i>Number of buds per flowering stem</i> .—2.			
<i>Shape of individual bud</i> .—Napiform.			
<i>Length of individual bud</i> .—1.5-2 cm.			
<i>Width of individual bud</i> .—8 mm to 1 cm.			
<i>Bud color</i> .—143C.			
Natural flowering season at specified location: End of April to May in Gifu, Japan.			
Average number of flowers per year at specified location: 10 to 15.			
Flowering habit: Continuous and freely flowering.			
Flower description: 2 or more flowers and bloom like a bunch.			
Lastingness of an individual flower on the plant: 10 days to 2 weeks.			
Lastingness of a cut flower: 1 week.			
Flower:			
<i>General appearance</i> .—Double flowering rose.	55		
<i>Shape</i> .—Round and mounded.			
<i>Diameter</i> .—8-10 cm.			
<i>Height</i> .—3-4 cm.			
Petals:			
<i>Color</i> .—Upper surface (when opening): 67A. Lower surface (when opening): 67B. Upper surface (fully opened): 67A. Lower surface (fully opened): N66D.	60		
<i>Shape</i> .—Rounded with a wavy habit.			
<i>Length</i> .—4-5 cm.			
<i>Width</i> .—5-6 cm.			
<i>Apex shape</i> .—Round with a wide lip.			
<i>Base shape</i> .—Round and narrow.			
<i>Margin</i> .—Entire.			
<i>Number per flower</i> .—70.			
<i>Texture</i> .—Soft.			
<i>Reflex characteristics</i> .—None.			
<i>Presence of basal petal spots</i> .—None.			
<i>Petaloid description</i> .—Lightly fringed with semi-double flowering.			
Sepals:			
<i>Color</i> .—Upper and lower surfaces (when opening): 142C. Upper and lower surfaces (fully opened): 142B.			
<i>Shape</i> .—Sharp.			
<i>Length</i> .—2-3 cm.			
<i>Width</i> .—8 mm to 1 cm.			
<i>Apex shape</i> .—Pointed.	20		
<i>Base shape</i> .—Wide.			
<i>Margin</i> .—Entire and tight, when closed.			
<i>Number per flower</i> .—4-5.			
<i>Texture</i> .—Soft.			
Pedicel:			
<i>Length</i> .—3-5 cm.			
<i>Diameter</i> .—3 mm.			
<i>Texture</i> .—Soft and smooth.			
<i>Strength</i> .—Strong.			
<i>Color</i> .—142B.			
Peduncle color: 141D.			
Receptacle:			
<i>Texture</i> .—Soft and smooth.			
<i>Shape</i> .—Semicircle.			
<i>Height</i> .—5-7 mm.			
<i>Width</i> .—5-7 mm.			
<i>Color</i> .—157A.			
Fragrance: Strong.			
Disease/pest resistance: Average resistance to powdery mildew of the <i>Erysiphaceae</i> family.	40		
Winter temperature tolerance: Blooming at 1° C. in winter. With only roots, -15~-18° C.			
Hot temperature tolerance: 40° C.			
Drought tolerance: Average.			
Reproductive organs:			
Stamens:			
<i>Number (per flower)</i> .—50.			
<i>Filament</i> .—Length: 7-10 mm. Color: 158D.			
<i>Anthers</i> .—Shape: Like a match stick. Length: 2-3 mm. Color: 168A.			
<i>Pollen</i> .—Color: 10D. Amount (generally): Less than average.			
Pistils:			
<i>Number</i> .—30.			
<i>Length</i> .—1-2 mm.			
<i>Style</i> .—Length: Average. Color: 160B.			
<i>Sigma</i> .—Shape: Funnel. Color: 160A. Size: 1 mm.			
<i>Ovaries</i> .—Length: 3 mm. Width: 0.5 mm. Color: 160B.			
I claim:			
1. A new and distinct variety of rose plant, as is herein illustrated and described.
